UNITED STATES PATENT OFFICE.

STEPHEN G. WILSON, OF PHILADELPHIA, PENNSYLVANIA.

WHISK.

Application filed April 30, 1924. Serial No. 709,962.

To all whom it may concern:

Be it known that I, STEPHEN G. WILSON, a citizen of the United States, residing at Philadelphia, county of Philadelphia, State 5 of Pennsylvania, have invented a new and useful Whisk, of which the following is a specification.

In whisks as heretofore manufactured, the whisks are thrown away when the straws 10 are worn out. In whisks of the better grade, an ornamental handle is employed and in many cases an ornamental shield is provided which surrounds the head of the whisk.

One of the main objects of my present invention is to devise a novel whisk wherein 15 when the straws are worn out the whisk can be replaced by a new one and the handle locking mechanism and shield can be used again.

20 With the above and other objects in view which will hereinafter appear, my invention comprehends a novel construction of a whisk.

It further comprehends a novel construction 25 of a dowel stick and novel locking mechanism to secure the handle on the dowel stick so that the handle can be removed when desired.

Other novel features of construction and 30 advantage will hereinafter more clearly appear in the detailed description and the appended claims.

For the purpose of illustrating the invention, I have shown in the accompanying 35 drawing a typical embodiment of it, which, in practice, will give reliable and satisfactory results. It is however to be understood that this embodiment is typical only and that the various instrumentalities of which my invention 40 consists can be variously arranged and organized, and that the invention is not limited to the precise arrangement and organization of these instrumentalities as herein set forth.

45 Figure 1 represents, in front elevation, a whisk embodying my invention.

Figure 2 represents, in front elevation and in detached position, of the locking mechanism.

50 Figure 3 represents, in side elevation, the parts seen in Figure 2.

Figure 4 represents, in front elevation, a spring employed.

55 Figure 5 represents a section on line 5—5 of Figure 7.

Figure 6 represents a top plan view of a washer.

Figure 7 represents a vertical section of the whisk.

Figure 8 represents, in front elevation, 60 and in detached position, the dowel stick.

Figure 9 represents a section on line 9—9 of Figure 8.

Similar numerals of reference indicate 65 corresponding parts.

Referring to the drawings:

1 designates a whisk embodying my invention. 2 is the dowel stick to which are connected the inner or corner straws 3 by means of the wire 4, and, in a similar manner, the outer straws 5 are connected to the dowel stick by the wire 6.

The dowel stick has a tapered slot, the side walls of which converge towards and open through the upper end of the dowel stick. 75 7 is an aperture opening into the slot 8. 10 designates the grasping handle which is apertured as at 11 to receive the dowel stick. The walls of the aperture 11 near the top are tapered or converge towards the upper end 80 of the handle as at 12 forming an opening through the top of lesser diameter, and the handle portion surrounding the upper end of the aperture 11 is recessed as at 13 to receive a plate or washer 14. Extending outwardly from about the center of the plate 14 as at 15 is a slot 16.

85 The handle 10 is secured to the dowel stick by means of novel locking mechanism which I will now describe.

90 17 designates a key having in its grasping portion one or more apertures 18 to enable one to hang the whisk on a nail or other support. The head 19 of the key is split longitudinally as at 20 and opposite edges 21 converge or taper upwardly. The inner end of the head is of reduced diameter as at 22 in order to enter the aperture, 8 in the dowel stick. The head is provided with an anchor or head 23 which has an aperture 95 24 through it which is preferably rectangular. 25 designates a spring having its inner end offset as at 26, and its outer end is of reduced diameter as at 27. The spring passes through the aperture 24 so that opposite edges engage the tapered diverging walls 28, and the portion 26 overhangs the head portion 22. The head above the anchor 100 is cut out at opposite sides as at 29.

105 The parts when assembled appear as in 110

Figure 7. The shield 9 is placed in position on the head of the whisk and the handle 10 is placed on the dowel stick 2. The locking mechanism as shown in Figure 2 is then inserted into the narrow part of the slot 7 in the dowel stick. The key is then given a quarter turn to bring the parts into the position seen in Figure 7. The tapered sides 21 engage the tapered walls of the slot 7. The lower end of the locking spring is in the aperture 8 in the dowel stick and the locking end 27 moves outwardly in the slot 16 into the position seen in Figure 3. The key has the recesses 30, so that when the key is turned in the slot 16, it locks with the plate 14 as shown in Figure 7. It will be apparent that when the spring is in the position seen in Figure 3 the key cannot be turned, and the spring must be pressed inwardly before the key can be moved into its unlocked position and withdrawn.

The dowel sticks are usually made of wood and the slots vary a little in size when manufactured. For this reason I provide the taper 12, so that when the handle is being locked in position, the upper end of the dowel stick will be compressed to a desired degree and the tapered walls of the key head will always engage the tapered walls of the slot in the dowel stick as the closing action of the dowel stick will be more rapid than the downward movement of the key.

When the locking portion or spring 27 of the key is pressed inwardly, the key can be turned and with the spring and plate withdrawn from the dowel stick. The handle and shield can then be removed to renew the wornout whisk.

The width of the spring is slightly less than the length of the slot 16 in the plate 1.

When the spring is passed through the opening in the key head it overlaps the head on both sides and prevents the twisting of the parts of the shank when the key is turned into locking position. As the key is turned into its locking position the sharp points of the anchor portion will be imbedded into the wood of the walls of the tapered slot of the dowel stick. The spring resting against the opposite slanting edges of the walls of the aperture in the head prevents the head from drawing together and retains the key in the spread position into which it has been set so that the proper fit will be obtained with the walls of the tapered slot of the dowel stick.

It will be apparent that when the key is withdrawn the plate will be withdrawn with it. After the spring plate and key have been assembled together they remain together as a unit of structure and are insertible into assembled position and removable from assembled position as a unit of structure.

The function of the slot in the head of

the key is to enable one to spread the head or bring it together so that the proper fit will be obtained with the variations of the tapered slot in the dowel stick. When the key is spread to fit the slot in the dowel stick 70 it will be apparent that the spring bears against the tapered walls in the aperture of the head and will retain the key in the spread position to which it has been set.

It will now be apparent that I have devised a new and useful whisk which embodies the features of advantage enumerated as desirable in the statement of the invention and the above description, and while I have, in the present instance, shown and 75 described a preferred embodiment thereof which will give in practice satisfactory and reliable results, it is to be understood that this embodiment is susceptible of modification in various particulars without departing from 80 the spirit or scope of the invention or sacrificing any of its advantages.

Having thus described my invention, what I claim as new and desire to secure by Letters Patent, is:

1. In a whisk, the combination with a dowel stick having an undercut slot at its outer end, of a tubular handle slidable on said stick, and a key arranged in the upper end of the handle having a head adapted to enter the slot in the stick, said head being provided with a diverging side adapted to be rotated to engage the undercut wall of said dowel stick slot for interlocking said parts, and releasable means for holding said parts in interlocked position.

2. In a whisk, the combination with a dowel stick having an undercut slot at its outer end, of a tubular handle slidable on said stick, a plate engaging said handle having a slot, a key arranged in the upper end of the handle, adapted to pass through said plate slot and being provided with a head having a diverging side adapted to be rotated to engage the undercut wall of said 95 dowel stick slot, and a spring fulcrumed on said key and adapted to interlock with said plate and to bear against the wall of said dowel stick slot.

3. In a whisk, the combination with a 105 dowel stick having an undercut slot at its outer end, of a tubular handle slidable on said stick and having the outer end of its bore tapering, a plate on said handle having a slot, a key having a head adapted to pass through said plate slot and into the dowel stick slot and provided with tapered sides to engage when rotated the walls of said 115 dowel stick slot, and a spring fulcrumed on said key head and having one end extending through the slot of said plate.

4. In a whisk, the combination with a 120 dowel stick, having an undercut slot at its outer end and having a recess opening into said slot, of a tubular handle slidable on said 125

stick, a plate engaging said handle and provided with a slot, a key having a tapered head adapted to pass through the slot of said plate and adapted when the key is turned 5 to engage the walls of the dowel stick slot, and a spring carried by said key head, passing through the slot of said plate and bearing against the wall of said recess to prevent the turning of said key.

10 5. In a whisk, the combination with a dowel stick having an undercut slot at its outer end, of a tubular handle slidable on said stick, a plate contacting with the outer end of said handle and having a slot, a key 15 having a split head with tapered side walls and an aperture at its inner end and adapted to pass through the slot of said plate, and a spring passing through said aperture, the lower end of said spring overhanging said 20 head, and the upper end of said spring passing through the slot of said plate.

6. In a whisk, the combination with a dowel stick having an undercut slot at its outer end, and having a recess opening into 25 said slot, of a tubular handle slidable on said stick, a plate having a slot contacting with said handle, a key having a tapered head passing through the slot of said plate, a shoulder abutting against said plate, said 30 head passing into the slot of said dowel stick and provided with a tapered wall which

when turned engages the wall of the dowel stick slot, said head being split and having its forward end reduced to adapt it to enter said recess and provided in rear of said reduced portion with an anchor portion having a polygonal shaped aperture, and a spring passing through said polygonal shaped aperture and fulcrumed on the walls thereof, the forward end of said spring overhanging said split head to prevent its twisting, and the other end of said spring extending through the slot of said plate. 35 40

7. In a whisk, the combination with a dowel stick having an undercut slot at its outer end, of a tubular handle slidable on said dowel stick, a plate and having a slot contacting with said handle, and a locking mechanism for said handle and dowel stick, comprising a key having a split head which 45 passes through and interlocks with said plate and which is provided at its forward end with an apertured anchor portion, the opposite walls of said head aperture being inclined to each other, and a spring passing through said head aperture and fulcrumed on said inclined walls, the forward end of said spring extending along said key head to prevent its twisting when turned, and the opposite end of said spring extending 50 55 60 through the slot of said plate.

STEPHEN G. WILSON.
